UNITED STATES PATENT OFFICE.

WESLEY E. COCHRAN, OF CLEVELAND, OHIO, ASSIGNOR TO THE ART METAL MANUFACTURING COMPANY, OF CLEVELAND, OHIO.

DIMMER.

1,208,487.

Specification of Letters Patent. Patented Dec. 12, 1916.

Application filed May 19, 1915. Serial No. 29,136.

To all whom it may concern:

Be it known that I, WESLEY E. COCHRAN, a citizen of the United States, residing at Cleveland, in the county of Cuyahoga and 5 State of Ohio, have invented a new and useful Dimmer, of which the following is a specification.

The device forming the subject matter of this application is a dimmer or shield adapted to be applied to an electric light bulb of 10 that type commonly employed upon automobiles.

The dimmer forming the subject matter of this application is adapted to be snapped 15 onto the bulb and to rotate thereon.

The invention aims particularly to provide novel means whereby the dimmer may be held upon the metal shank of the bulb for rotation.

20 It is within the province of the disclosure to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that 30 changes in the precise embodiment of the invention herein disclosed can be made within the scope of what is claimed, without departing from the spirit of the invention.

In the accompanying drawing:—Figure 1 35 shows the invention, side elevation; Fig. 2 is an elevation showing one end of the structure; Fig. 3 is an elevation showing the opposite end of the structure; Fig. 4 is a section taken approximately on the line 4—4 of 40 Fig. 2; Fig. 5 is a fragmental perspective showing a portion of the dimmer.

The dimmer forming the subject matter of this application preferably is made of metal throughout and is a one piece structure, the 45 interior of the dimmer being enameled, silvered, or otherwise constructed to afford an efficient reflecting surface.

The dimmer comprises a body 1 of hemispherical form, having a flaring marginal 50 flange 2. The body 1 and the flange 2 con-

stitute a shell in which is formed, near one edge of the shell, an opening designated by the reference character 3 and preferably of circular outline. Opposite to the opening 3, the flange 2 is provided with a marginal 55 notch 4 located opposite to the opening 3, the flaring disposition of the flange 2 with respect to the body 1 serving to form, at the points where the notch 4 intersects the outer edge of the flange 2, a pair of resilient, approaching, gripping prongs which extend outwardly beyond the spherical surface defined by the outer face of the body 1. In practice, there is no prominent and distinct line of demarcation between the body 1 and 60 the flange 2, the flange, however, flaring sufficiently to throw the prongs 5 outwardly, as clearly shown in Fig. 5.

The invention is adapted to be employed in combination with an electric lamp embodying a bulb 6 having a teat 7 and a metal shank 8. The bulb 6 is of spherical outline.

In practical operation, the teat 7 is thrust through the opening 3 and the shank 8 is received in the notch 4. Since the body 1 is 70 of hemispherical form, it is obvious that the prongs 5 extend past the diameter of the shank 8 and constitute a means whereby the dimmer is held for rotation on the lamp, it being possible to rotate the dimmer so that 75 it may shield any part of the bulb 6.

Especial attention is directed to the flaring flange 2, and to the prongs 5. Since the flange flares and since the notch 4 intersects the flange, the prongs 5 are made to extend 85 outwardly beyond the spherical surface defined by the outer face of the body 1 and consequently, these prongs are given a resiliency which they would not possess if the device were otherwise constructed. It is possible, 90 therefore, to snap the shank 8 readily within the contour of the notch 4.

Having thus described the invention, what is claimed is:—

A dimmer for electric lamp bulbs, comprising a hemi-spherical body provided with a teat-receiving journaling opening located within the contour of the body, and provided in its edge with a parti-circular notch located opposite to the opening, the constitu- 95 100

ent material of the body being continuous adjacent the notch, the geometrical center of the notch being set back from the edge of the body, whereby the edge of the notch will cooperate with the edge of the body to form acutely pointed gripping prongs which project toward each other.

In testimony that I claim the foregoing as my own, I have hereto affixed my signature in the presence of two witnesses.

WESLEY E. COCHRAN.
